APPARATUS FOR SHARPENING FILES

August A. Roth, Baltimore, Md.

Application August 5, 1932. Serial No. 627,645

8 Claims. (Cl. 204—5)

This invention relates to apparatus particularly designed for sharpening files by means of an electrolyte and a current, as described in my co-pending application entitled Apparatus for sharpening tools, filed October 23, 1931, Serial Number 570,685.

The principal object of the invention is to provide apparatus in which spotting of the electrolyte due to uneven distribution of current will 10 be positively eliminated so that the electrolyte may be used over and over again, if desired.

Another object of the present invention is to provide an improved heating tank having an immersed electric heater therein whereby the water which forms the heating medium for the electrolyte will be more quickly brought to, and more uniformly maintained at, the desired operating temperature than hitherto possible.

A further object is to provide an improved 20 mounting in the tank for the earthen vessel which contains the electrolyte, to the end that the vessel may be readily removed and replaced, and when in operative position will be supported directly upon a grid so that the current may find easy 25 metal paths across the earthen vessel to expedite the sharpening operation.

A further object is to provide a novel holder for the files which will permit the files being supported upright and stationary during the sharpening process.

A further object is to provide a novel cover for the tank adapted to permit escape of vapors and to permit replenishing the water supply in the tank without disturbing the earthen vessel.

With the above and other objects in view the invention consists in certain novel details of construction and combinations of parts herein-after fully described and claimed it being understood that various modifications may be resorted 35 to within the scope of the appended claims without departing from the spirit or sacrificing any of the advantages of the invention.

In the accompanying drawings forming part of this specification,

Figure 1 is a vertical section through the apparatus,

Figure 2 is a plan view of the apparatus,

Figure 3 is a plan view of the tank with the earthen vessel removed and showing the cathode and the immersed electric heaters,

Figure 4 is a detail horizontal section showing the mounting of the immersed heaters,

Figure 5 is a front elevation of the mounting 55 and heaters,

Figure 6 is a plan view of the bottom plate of the holder,

Figure 7 is a plan view of a modified form of holder,

Figure 8 is a cross section taken on the line 60 8—8 of Figure 7,

Figure 9 is a detail section through the lower part of the apparatus showing a gas heater substituted for the electric heater, and

Figure 10 is a diagrammatic view showing the 65 electric wiring of the apparatus.

As is well known, ordinary methods of sharpening tools, such as dental burrs, files and like multi-edged tools, by an electrolyte and an electric current, is unsatisfactory due to pitting of 70 the tools, as well as the formation of an objectionable taper, that is sharpening of the cutting edges on the side of the tool toward the positive electrode, and insufficient sharpening on the side away from the electrode.

Also spotting of the electrolyte occurs, that is, deterioration in spots due to uneven distribution of current so that such spots differ in strength from adjoining portions of the electrolyte and this spotting not only destroys the 80 electrolyte and renders it unfit for further continued use but also aggravates the condition known as pitting and the opposite condition, that is, the formation of deposits on the tools to be sharpened.

The present apparatus is designed to correct these disadvantages by the provision of a novel earthen vessel which contains an electrolyte in which the files to be sharpened are submerged and a novel water tank in which the vessel is 90 placed, the water in the tank being uniformly heated throughout to promote the flow of current uniformly in all directions to and from the submerged files so that uniform sharpening will be effected throughout the entire superficial area 95 of the cutting edges of the files, and spotting positively eliminated.

Ordinarily, difficulty has been experienced in bringing the temperature of the water in the tank up to the required operating temperature 100 of about 140° F. to 160° F. and maintaining it for the three minute, more or less, time period necessary to effect the sharpening, so that long, wasteful delays are encountered as well as changes in temperature throughout the period. The present invention obviates this disadvantage by the provision of a plurality of electric heaters which are submerged in the water and heat the bath direct without intervening walls, the heaters being adapted to quickly bring the water up to the 105 110

operating temperature and maintain it at this temperature during the sharpening operation so that the guess work encountered in apparatus hitherto proposed is entirely eliminated.

5 Referring now to the drawings in which like characters of reference designate similar parts in the various views, the apparatus is shown to comprise a cylindrical metal tank 10 preferably having double walls 11 between which a packing 10 of heat insulating material 12, such as asbestos is interposed. The walls are preferably formed of metal. Preferably, also the inner wall is provided above its bottom edge with a circumferential flange 13 upon which the bottom edge of 15 the outer wall rests. The outer wall may be reinforced with split reinforcing hoops 14, the ends of which are tied together by means of an eye 15 on one end and a threaded projection 16 on the other end having a nut 17, which may be 20 tightened against the eye, to draw the hoops snugly in place, as shown in Figure 2.

The tank is provided preferably with a sheet metal bottom 18 which is provided with a flange 19 that extends downwardly along the inner wall 25 of the tank and reinforces the same against distortion. The bottom may be welded, or otherwise rigidly secured to the tank wall.

The tank is provided at the top edge of the inner wall with a circumferential flange 20 upon 30 which rests a cover 21, preferably formed of sheet metal. The cover is provided with a central opening 22 of sufficient size to loosely receive the hereinafter described earthen vessel 23 and the cover slopes downwardly from the outer 35 periphery thereof to said opening so that the contents of the tank may be replenished from time to time by pouring water on to said cover from whence it passes downwardly through the opening 22 into the tank. The opening 22 also 40 permits escape of vapors from the tank. The cover is provided with a downwardly extending flange 24 which surrounds the upper portion of the outer wall of the tank, as shown.

The tank is adapted to be filled with water to 45 nearly the top thereof, and for heating the water directly, preferably a pair of immersed electric heaters 25, shown best in Figure 4, are mounted in an opening 26 formed in the inner wall of the tank. These heaters extend parallel 50 with the bottom of the tank and are elevated slightly above the bottom and are sufficient in length to extend to substantially the axis of the tank, as shown best in Figure 3.

For mounting the heaters, a substantially oval 55 casting 27, shown best in Figure 5, is provided with a pair of threaded openings 28 into which the screw threaded insulating bushings 29 of the heaters are received. The casting is provided at the ends with ears 30 which may be welded to the outer surface of the inner wall of the tank. The casting is provided also with a substantially oval flange 31 which projects through the opening 26 and forms a guard flange around the bases of the heating elements 32 inside the tank. The 60 flange is welded or otherwise rigidly secured to the edge of the opening 26 to prevent leakage therethrough.

The heaters are of standard type that may be procured on the market and embody as an essential feature a loop resistance element 33 which is engaged in a sheath 34 of high heat conductivity material which prevents water coming in contact with the resistance elements.

As best shown in Figure 4, the outer wall of the tank is bent inwardly around the casting to pro-

vide a flange 35 which holds the asbestos packing 12 in place and also defines an opening in the outer wall of the tank to permit easy insertion and removal of the heaters.

Referring again to Figure 1, it will be seen 80 that the earthen vessel is cylindrical in contour. The vessel is preferably an earthen cylindrical jar and may be either glazed or unglazed, but should be of sufficient porosity to permit the electrolyte 36, with which the vessel is filled, to 85 dampen the jar throughout its physical structure and form easy paths for the current from the electrolyte in the jar to the water in the tank and from thence through the tank, which forms a part of the cathode, to the low tension terminal 90 of the source of current supply.

By referring to Figure 10, it will be seen that 95 one of the heaters may be connected to any suitable source of alternating current supply by means of circuit wires 37 and 38 controlled by a switch 39 to deliver about 3000 watts, more or less. The other heater is connected by circuit wires 39 and 40 to the source of alternating current, these wires being controlled by a pair of switches 41 and 42 which are selectively closed 100 to deliver either 1500 or 3000 watts to the heater. As will be apparent, when the switches 39, 41 and 42 are all closed both heating coils will be energized to maximum capacity for quickly heating the water in the tank. By opening the switch 105 39 only one of the heaters will be energized and by then opening the switches 41 or 42 said heater will be only partly energized. Thus a predetermined temperature of the fluid in the tank may be maintained after it is quickly brought up to 110 the operating temperature of from about 140° F. to 160° F. The heated water bath in the tank produces a corresponding temperature in the electrolyte by conduction through the earthen vessel 23.

As best shown in Figure 1, the files to be sharpened are secured in a holder preferably consisting of an upper disk 43 and a lower disk 44, preferably formed of sheet copper. A spacing block 45, of insulating material such as "bake-lite", is interposed between the disks and is provided with an upstanding boss 46 which projects through a central opening in the upper disk. The boss is interiorly threaded to receive the threaded lower end of a tube 47 which is sufficient in height to extend above the top of the vessel 23. The block is secured to both disks by means of bolts 48. The disks are, furthermore, held in spaced relation by bolts 49 upon which are disposed spacing sleeves 50, these spacing sleeves being disposed between the disks. The bolts, furthermore, are sufficient in length to extend below the bottom disk 44 and have threaded upon them sleeves 51 which form legs to support the disks upon the bottom of the earthen 135 vessel 23.

The holder is thus supported stationary on the bottom of the vessel. Both the insulating block 45 and the lower disk 44 are provided with aligned square central openings, as shown, to 140 reduce weight of these parts. As shown best in Figures 2 and 6, the upper disk is provided with a plurality of oblong openings 55 and the lower disk is provided with a plurality of small 145 circular openings 56 which align with respective ones of the oblong openings 55. The files 57, to be sharpened, are mounted on the disks in upright position by passing the shank of each file downwardly through an oblong opening 55 150

and through a corresponding circular opening 56, as shown in Figure 1.

The tube 47 of the holder terminates at the top in a ring 58 adapted to receive preferably the "bakelite" link of a block and tackle, or other hoisting means for lifting the holder with its files out of the electrolyte after the sharpening operation and replacing the holder in the electrolyte filled with the dull files to be sharpened.

10 By referring to Figure 1, it will be seen that the tube 47 is provided with an insulated conductor wire 59, the lower end of which is divided into two strands 60 which pass laterally through an opening 61 formed in the "bakelite" block 45 and are terminally connected to the above mentioned bolts 48. Also an insulated wire 62 is bared at spaced points 63 and secured at the bared points to the metal cylindrical base flange 19 of the tank, by means of bolts 64. A conductor wire 65 is also connected to one of these bolts and leads to any suitable source of electric current, such as a 110 volt alternating house current, as shown best in Figure 10.

As also shown in said figure, the wire 59, carried by the tube 47, is connected to said source of current and preferably a rheostat 66 or transformer, if preferred, is interposed in the circuit with the wires 59 and 65 so that a low voltage, such as for instance two volts, may be maintained during the sharpening operation. The tank is insulated from its supporting cylindrical base, hereinafter described, as shown in Figure 1, so that the current passes from the rheostat through the wire 59, copper disks, files, electrolyte, damp wall of the earthen vessel, hot water, tank wall, and returns through the wire 65 to the rheostat. The direction of flow is the reverse from the above when the cycle reverses.

For supporting the vessel 23 in the water tank, 40 a plurality of angular metal brackets 67 are secured to the inner wall of the tank above the heaters and project radially underneath the vessel. Upon these brackets there is mounted a grid 68, of the general shape shown in Figure 3, and which comprises an outer ring 69, an inner ring 70 concentric therewith and a center boss 71, these parts being connected by arcuate spokes 72, while certain other arcuate spokes 73 connect the outer ring with the inner ring and terminate short of the boss. This grid is preferably formed of copper and is insulated from the bracket 67 by means of a ring 74 of "bakelite" or other suitable material. The insulating ring is provided with a circumferential upstanding flange 74' which engages the outer ring 69 of the grid and centers the grid on the brackets 67.

The earthen vessel 23 is mounted direct upon the grid 68. It will thus be apparent that the skeleton structure of the grid permits of the water in the tank contacting with the bottom face of the vessel so that the temperature of the water will readily be imparted to the bottom of the vessel, while at the same time the metal grid provides easy paths for the low voltage current passing to and from the electrolyte through the damp bottom of the vessel in a general radial direction across the bottom of the vessel.

It will be apparent that since the earthen vessel is nested within the metal tank in contact with the hot water in the latter, the electric current will flow from the axis of the vessel radially through the heated electrolyte and through the files to all points of the wall of the tank. Consequently, when alternating, pulsating, or reversing current is used, the copper in the electro-

lyte will be deposited uniformly through the entire surface of each file and then carried off therefrom when the cycle reverses, to cause a uniform cut, or removal of a thin skin of the file throughout the entire superficial area thereof so that uniform sharpening of the cutting edges will be produced, and objectionable taper positively obviated. At the same time, due to the uniform flow of current, through the uniformly heated water bath in the tank, spotting of the electrolyte will be eliminated and the objectionable pitting and deposits caused by spotting will consequently be positively obviated.

The above mentioned base for supporting the tank is designated by the numeral 75. It is preferably formed of steel and is cylindrical in contour and is of sufficient diameter to permit of the tank loosely telescoping therein for a short distance, as shown in Figure 1. The base is insulated from the tank wall by a ring 76 of "bakelite", or other suitable material. A plurality of angle brackets 94, similar to the vessel supporting brackets 67, are secured to the inner surface of the base and extend radially underneath the tank to support the weight of the tank 100 and its contents. A ring 95 of "bakelite" or other suitable material is interposed between the brackets and the bottom of the tank to insulate the tank bottom from the base.

The base may also be provided with a hinged 105 door 77 through which access to a gas heater 78, to be used for demonstration or for experimental purposes where electric current is not available. may be had. The burner is best shown in Figure 9, and may be of the ordinary type equipped with 110 an air valve 79. The burner may be located directly underneath the bottom of the tank so as to discharge its flame upwardly against the bottom of the tank.

The base is also provided in its wall with an 115 opening 80 through which a pipe 81, carried by the bottom of the tank, projects, as shown. The lateral arm 82 of the pipe is threaded into the T coupling 83 of the pipe so as to permit of said arm being removed so that the tank may be detached from the base when necessary. This pipe may be used as a steam pipe to heat the water in the tank, if desired, or may be used as a drain pipe, if desired, or even to fill the tank.

In some instances, it will be desirable to suspend the files without removing their handles, as shown in Figure 8, in the electrolyte. For this purpose a holder is provided comprising a copper disk 84 having a plurality of radially disposed slots 85 and 86 extending from the outer 130 edge toward the axis of the disk. The slots 85 are short and the slots 86 are relatively long and alternate. The files 87, equipped with their handles 88, may be inserted downward through the slots until the handles engage the disk and support the files on the disk but extending below the disk.

A tube 89 is threaded into the center of the disk and is equipped with a hook 90 for engagement with the "bakelite" link 91 of a suitable 140 hoisting apparatus for raising the disk out of the electrolyte and for lowering it into the electrolyte. A circuit wire 92 is secured by a screw 93 to the metal tube 89, as above described.

Preferably the electrolyte comprises a mixture of copper sulphate, sulphuric acid, borax, and acetic acid.

From the above description it is thought that the construction and operation of my invention 150

will be fully understood without further explanation.

What is claimed is:

1. Apparatus for sharpening files comprising a tank adapted to be filled with water, an electric heater immersed in the tank for heating the water, means for connecting the heater to a source of current supply, an earthen vessel nested within the tank in contact with the water and adapted to contain an electrolyte, a holder for supporting the files in the vessel in contact with the electrolyte, and means for connecting the tank and the holder in circuit with said source of electricity. 80
2. Apparatus for sharpening files comprising a metal tank adapted to be filled with water, a metal base for the tank forming a compartment below the tank, said tank having a heat insulated wall, an electric heater immersed in the tank near the bottom, a casting in said wall of the tank removably supporting said heater, an earthen vessel nested within the tank adapted to be heated by contact with the water and adapted to contain an electrolyte, a holder for supporting files in the vessel in contact with the electrolyte, means for connecting the tank and the holder in circuit with a source of electricity, and means for connecting said heater with said source of electricity. 85
3. Apparatus for sharpening files comprising a metal tank adapted to contain water, an electric heater immersed in the tank near the bottom thereof, a metal grid concentrically disposed in the tank and insulated from the inner surface of the tank, an earthen vessel supported in the tank on said grid and adapted to be filled with an electrolyte, a holder for supporting files in the electrolyte in upright position above said grid, means for connecting the tank and the holder in circuit with a source of electricity, and means for connecting said heater with said source of electricity. 90
4. Apparatus for sharpening files comprising a metal tank adapted to be filled with water, an electric heater carried by the wall of the tank and projecting axially to approximately the center of the tank for heating the water, brackets carried by the inner wall of the tank, an insulating ring carried by the brackets, a metal grid supported by said ring having curved radial spokes extending toward the axis of the tank, an earthen vessel in the tank supported upon said grid and adapted to be filled with an electrolyte, a holder for supporting files in the vessel in contact with the electrolyte above the grid, means for connecting the tank and holder in circuit with a source of alternating current, and means for connecting said heater with said source of electricity. 95
5. Apparatus for sharpening files comprising a metal tank adapted to contain water, an earthen vessel supported axially in the tank in contact with the water and adapted to contain an electrolyte, an electric heater carried by the wall of the tank and immersed in the water below the bottom of the vessel, a file holder submerged in the electrolyte, means carried by the holder for supporting files in upright position in the electrolyte, circuit wires connecting said holder and said tank with a source of alternating current, a rheostat for varying the voltage of the current carried by said circuit wires, and circuit wires connecting the heater with said source of current. 100
6. Apparatus for sharpening files comprising a metal tank adapted to contain water, an earthen vessel supported axially on the tank and spaced above the bottom thereof and adapted to contain an electrolyte, an electric heater carried by the wall of the tank below the bottom of the vessel and above the bottom of the tank, a cover for the tank having a central opening loosely receiving the vessel and permitting escape of vapors from the tank, said cover sloping downwardly from the wall of the tank to said opening whereby water may be poured on to the cover to escape downwardly through said opening for replenishing the tank, a file holder removably disposed within the earthen vessel in contact with the electrolyte, means for connecting said holder and said tank in circuit with a source of electricity, and means for connecting said heater with said source of electricity. 105
7. Apparatus for sharpening files comprising a metal tank adapted to contain water, an electrical heater, an earthen vessel adapted to be suspended axially in the tank and adapted to contain an electrolyte, a file holder removably disposed axially in the vessel and having a pair of spaced disks provided with aligned openings to receive the shanks of the files and support the files upright in the electrolyte, legs on the lowermost disk for supporting the holder on the bottom of the vessel, means for connecting the holder and the tank in circuit with a source of electricity, and means for connecting the heater in circuit with said source of electricity. 110
8. Apparatus for sharpening files comprising a metal tank adapted to be filled with water, an electric heater immersed in the tank, an earthen vessel disposed axially in the tank and adapted to contain an electrolyte, a file holder suspended in the vessel in contact with the electrolyte and having a slotted disk adapted to receive the files and engage the file handles to support the files in the electrolyte below the disk, means for connecting the tank and the holder in circuit with a source of electricity, and means for connecting the heater with said source of electricity. 115
9. Apparatus for sharpening files comprising a metal tank adapted to be filled with water, an electric heater carried by the wall of the tank and immersed in the water below the bottom of the vessel, a file holder submerged in the electrolyte, means carried by the holder for supporting files in upright position in the electrolyte, circuit wires connecting said holder and said tank with a source of alternating current, a rheostat for varying the voltage of the current carried by said circuit wires, and circuit wires connecting the heater with said source of current. 120
10. Apparatus for sharpening files comprising a metal tank adapted to be filled with water, an electric heater carried by the wall of the tank and immersed in the water below the bottom of the vessel, a file holder submerged in the electrolyte, means carried by the holder for supporting files in upright position in the electrolyte, circuit wires connecting said holder and said tank with a source of alternating current, a rheostat for varying the voltage of the current carried by said circuit wires, and circuit wires connecting the heater with said source of electricity. 125
11. Apparatus for sharpening files comprising a metal tank adapted to be filled with water, an electric heater carried by the wall of the tank and immersed in the water below the bottom of the vessel, a file holder submerged in the electrolyte, means carried by the holder for supporting files in upright position in the electrolyte, circuit wires connecting said holder and said tank with a source of alternating current, a rheostat for varying the voltage of the current carried by said circuit wires, and circuit wires connecting the heater with said source of electricity. 130
12. Apparatus for sharpening files comprising a metal tank adapted to be filled with water, an electric heater carried by the wall of the tank and immersed in the water below the bottom of the vessel, a file holder submerged in the electrolyte, means carried by the holder for supporting files in upright position in the electrolyte, circuit wires connecting said holder and said tank with a source of alternating current, a rheostat for varying the voltage of the current carried by said circuit wires, and circuit wires connecting the heater with said source of electricity. 135

AUGUST A. ROTH. [L.S.]
